UNITED STATES PATENT OFFICE

138,681

DESIGN FOR A PARKING METER HOUSING OR SIMILAR ARTICLE

Ernest Victor Nelson, Clarendon Hills, Ill., assignor to Miller Meters, Inc., Chicago, Ill., a corporation of Illinois

Application June 12, 1944, Serial No. 113,973

Term of patent 14 years

(Cl. D52—2)

To all whom it may concern:

Be it known that I, Ernest Victor Nelson, a citizen of the United States and residing in the town of Clarendon Hills, in the county of Cook and State of Illinois, have invented a new, original, and ornamental Design for a Parking Meter Housing or Similar Article, of which the following is the specification, reference being had to the accompanying drawing forming a part thereof.

On the drawing:

Fig. 1 is a front elevational view of a parking meter housing, showing my new design;

Fig. 2 is a rear elevational view; and

Fig. 3 is a side elevational view.

Fig. 4 is a top plan view thereof.

I claim:

The ornamental design for a parking meter housing or similar article, substantially as shown.

ERNEST VICTOR NELSON.
